Primary Examiner — Cathron Brooks*Assistant Examiner* — Andrew Nemeth(74) *Attorney, Agent, or Firm* — McAndrews Held & Malloy, Ltd.(57) **CLAIM**

The ornamental design for a display screen or portion thereof with icon, as shown and described.

DESCRIPTION

FIG. 1 is a front view of a display screen or portion thereof with icon showing our new design; and,

FIG. 2 is an enlarged view of the icon of FIG. 1.

The broken lines in FIG. 1 show a display screen or portion thereof and form no part of the claimed design.

1 Claim, 2 Drawing Sheets(56)
